DESIGN FOR AN ASCOT SCARF OR SIMILAR ARTICLE

Claire Clawson, New York, N. Y.

Application April 11, 1939, Serial No. 84,202

Term of patent 3½ years

To all whom it may concern:

Be it known that I, Claire Clawson, a citizen of the United States, residing at the city of New York, in the county of New York and the State of New York, have invented a new, original, and ornamental Design for an Ascot Scarf or Similar Article, of which the following is a specification, reference being had to the accompanying drawing, forming part thereof.

Fig. 1 is a plan view of the Ascot scarf or similar article showing my new design.

Fig. 2 is an edge view thereof.

My ornamental design consists of an article of apparel comprising a fabric which is designed in the manner as shown in the accompanying drawing.

I claim:

The ornamental design for an Ascot scarf or similar article, substantially as shown and described.

CLAIRES CLAWSON.
